UNITED STATES PATENT OFFICE.

THOMAS F. MOORE, OF WESTFIELD, NEW JERSEY.

TRENCHING APPARATUS.

1,305,396.

Specification of Letters Patent.

Patented June 3, 1919.

Continuation in part of application Serial No. 69,217, filed December 29, 1915. This application filed March 8, 1917. Serial No. 153,422.

To all whom it may concern:

Be it known that I, THOMAS F. MOORE, a citizen of the United States of America, and resident of Westfield, in the county of Union, in the State of New Jersey, have invented new and useful Improvements in Trenching Apparatus, of which the following, taken in connection with the accompanying drawings, is a full, clear, and exact 10 description.

This invention relates to certain improvements in traveling cranes as used more particularly in connection with the trenching apparatus forming the subject matter of my 15 pending application, Ser. No. 69,217, filed Dec. 29, 1915, of which the present application is, in part, a continuation.

The main object is to provide a more convenient and expeditious means for handling 20 the various materials used in the construction of trenches at any point along the trestle without materially interfering with traffic or the free operation of the excavating, hauling and re-filling apparatus.

25 One of the specific objects is to facilitate the placing and removal of the sheathing and bracing materials commonly used to retain the walls of the trench against caving in.

30 Other objects and uses will be brought out in the following description.

In the drawings—

Figure 1 is a cross sectional view of a portion of a trench and superposed trestle 35 showing my improved traveling crane or hoist in operative relation thereto for driving the sheathing into the ground.

Fig. 2 is a side elevation of the same crane and portions of its lower and upper 40 supporting rails.

Fig. 3 is a top plan of the upper portion of the crane showing more particularly its connection with the overhead track.

Fig. 4 is an enlarged detail sectional view 45 of the inner end of the upper crane carriage and adjacent portion of its supporting rail.

In carrying out my invention, an overhead I-beam —5— forming the central lengthwise ridge-rail of a suitable trestle 50 —3— and is supported directly over the center line of a proposed trench, as —A—, and carries upon its upper face a horizontally extending channel iron or track —40— having upstanding lengthwise flanges —40'— along its opposite edges for support-

ing and guiding the upper laterally extending arm —45— of a traveling crane —42—, presently described, the trestle being movable along the trench upon suitable rails —1—.

This crane comprises an upright frame or standard —44— and the substantially horizontal arm —45—, the standard —44— being provided with a relatively long horizontal base —44'— having rollers —43— on its opposite ends resting upon a guide-rail —1'— which runs along one side of and parallel with the trench and rails —1— to enable the crane to be easily and quickly shifted to any point where its use may be 70 required.

The arm —45— is pivoted at one end at —46— to the upper end of the standard —44— to swing vertically, and extends laterally therefrom over and above the overhead track —40— where it is widened lengthwise of the trench and provided with separate pairs of rollers —48— and —49—, for engaging either of the flanges —40'— of the track —40— and guiding the upper portion 80 of the crane in its lengthwise movement along the trench.

The object in pivoting the arm —45— to the standard is to allow it to automatically adjust itself to variations in the horizontal 85 parallelism of the lower and upper tracks —1'— and —40— and also to permit it to be readily detached from operative engagement with the overhead track —40— and folded upon the upright —44— in compact 90 space when not in use, as in storage or transportation.

The separate pairs of rollers —48— and —49— are spaced some distance apart at opposite sides of the longitudinal center of the arm —45— so as to retain the crane more nearly at right angles to the tracks —1'— and —40—, and at the same time to reduce to a minimum the liability of cramping or binding when shifted along said tracks. 95

The rollers —48— are journaled on horizontal bearings —48'— on a suitable bracket —45'— of the arm —45— to ride upon the upper face of the track —40— and against the inner face of one of the flanges —40'— to support said arm against downward movement, and also to hold the upper end of the crane against outward lateral movement relatively to said track so that the free or inner end of the arm is supported by its 110

own weight upon the track —40— and may be readily disengaged therefrom by upward displacement when it is desired to remove the crane from the trestle.

- 5 The rollers —49— are journaled on vertical bearings —49'— on the bracket —45— and engage the outer faces of the same flange —40'— to support and guide the upper portion of the crane against undue 10 inward movement, and at the same time permitting the arm to be readily disengaged from the track —40'— by upward movement when necessary, the rollers of each pair being preferably arranged nearly opposite 15 each other to better support the upper portion of the crane against undue lateral movement upon the track —40'.

The crane —42— is equipped with a suitable hoisting device consisting in this instance of a drum —68— and a driving shaft —68'—, both journaled upon the upright standard —44— within easy reaching distance of the operator and connected by suitable gearing for simultaneous action, the 25 shaft —68'— being provided with hand wheels —W— by which it may be rotated, while the gearing is adapted to be engaged by a pawl —p— for locking the drum and holding the load when necessary.

- 30 A cable —69— has one end attached to the drum —68— and its other end passed over an idler —70— on the arm —45— and provided with means, as a hook —69'—, for attachment to any object which it may be desired 35 sired to raise or lower or convey from one part of the trench to another.

As illustrated, the hook is attached to a weighted driver —71— for driving the sheathing —a— into the ground, but it may 40 be disconnected from the driver and the cable fastened to the sheathing to withdraw the latter and convey it to other localities along the trench for reinsertion or deposit.

- I have thus far described a single traveling 45 crane as used on one side of the trestle, but the channel iron —40— having two flanges —40'— permits the simultaneous and independent use of duplicate cranes, one at each side of the trestle, as shown in 50 Fig. 1, without interfering one with the other or with the fastening means, as the cap screws —72—, by which the channel bar is secured to the top face of the I-beam —5—, that is, either crane may be moved 55 along its corresponding guide flange —40'— independently of the other and used for similar or different purposes at any part of the trestle throughout its length, which greatly increases the range of use and efficiency 60 of apparatus of this character.

When duplicate cranes are used, they are interchangeable from one side to the other, or if, for any reason, a single crane is employed it may be used at either side of the 65 trestle with the same degree of efficiency by

simply removing it from the track or guide-rails at one side and replacing it upon the track and guide-rail upon the opposite side, this operation being greatly facilitated by the hinging of the main arm —45— to the 70 main upright support —44— which allows the arm —45— to be lifted to disengage the rollers —48— and —49— from one of the guide flanges —40'— whereupon the arm with the rollers thereon is folded downwardly against the main upright —44—, thus permitting the entire crane to be more readily shifted from one side of the trestle and replaced in operative position at the opposite side. 80

The operation of the device is clearly apparent from the foregoing description taken in connection with the accompanying drawings, and while I have shown it as particularly useful in connection with buildings 85 and removing the sheathing, it is evident that the hoisting device may be used for many other purposes, as previously explained.

What I claim is:

1. In a trenching apparatus, the combination of a trestle extending along the trenching line and a traveling crane movable along the outside of the trestle and having its upper portion overhanging the same in 95 traveling engagement therewith and carrying a part of the hoisting mechanism of the crane.

2. In a trenching apparatus, the combination of a trestle extending along the trenching line and provided with an overhead track and a traveling crane movable along the outside of the trestle and having a laterally projecting arm overhanging the trestle in traveling engagement with said track 100 and carrying a part of the hoisting means of the crane.

3. In a trenching apparatus, the combination of a trestle extending along the trenching line and a traveling crane movable 110 along the outside of the trestle and having a laterally projecting arm overhanging the trestle in traveling engagement therewith hinged to swing vertically out of said traveling engagement, said crane having a portion 115 of its hoisting means mounted on said arm.

4. In a trenching apparatus, the combination with a trestle extending along the trench-line, in combination with a track extending along the top of the trestle and provided with an upstanding lengthwise flange and a crane movable lengthwise of the trestle and provided with a laterally projecting arm having rollers thereon engaging opposite faces of the flange, said crane having portions of its hoisting mechanism mounted on 120 said arm.

5. In a trenching apparatus, the combination of a trestle extending along the trenching line and a traveling crane movable 125

along the outside of the trestle and having a portion thereof supported independently of the trestle and another portion overhanging said trestle and in traveling engagement therewith, said crane having a part of its hoisting mechanism mounted on said overhanging portion.

6. In a trenching apparatus, the combination of a trestle extending along the trenching line, a track running centrally lengthwise of and upon the trestle, and a traveling crane movable along the outside of the trestle and extending from the base to the top thereof and having its upper portion overhanging said top and riding upon the track, said crane having a part of its hoisting mechanism mounted on said overhanging portion.

7. In a trenching apparatus, the combination of a trestle movable along the trenching line and provided with an overhead track having an upstanding lengthwise flange, a traveling crane movable along the outside of the trench and having a laterally projecting arm provided with separate pairs of rollers at opposite sides of the longitudinal center of the arm, the rollers of each pair engaging opposite faces of the flange,

said crane having a part of its hoisting mechanism mounted upon said arm. 30

8. In a trenching apparatus, the combination of a trestle movable along the trenching line and provided with an overhead track having an upstanding lengthwise flange, a traveling crane movable along the 35 outside of the trench and having a laterally projecting arm pivoted at one end to swing vertically and having its opposite end provided with separate pairs of rollers, those of each pair engaging opposite faces of the 40 flange, said crane having a portion of its hoisting mechanism mounted upon said arm.

9. The combination with a trenching trestle, an overhead track mounted on the trestle and provided with parallel lengthwise guide 45 flanges in spaced relation, of separate traveling hoists movable along opposite sides of the trestle and having their upper portions guided on said flanges.

In witness whereof I have hereunto set my 50 hand this first day of March 1917.

THOMAS F. MOORE.
